EDGE-BURNISHING MACHINE

George Boulton, Rochester, N. Y., assignor to
United Shoe Machinery Corporation, Paterson,
N. J., a corporation of New Jersey

Application March 18, 1935, Serial No. 11,546

18 Claims. (Cl. 69—1)

This invention relates to machines for burnishing the edges of various articles, it being especially intended for finishing the exposed edges of shoe-parts which are not to be folded.

5 My invention has as an object the provision of a machine of the character above indicated, in which a burnishing member is effectively actuated and heated, in which the work is advantageously presented to said burnishing member, 10 and in which the operating elements are adjustable, so they may be positioned to best perform their functions. To this end, an oscillatory or otherwise movable burnishing tool is mounted upon a lever from which it extends toward the 15 plane of the work and in said plane. The lever is preferably actuated by a slide contacting with it and moved by an eccentric. The work may be advanced for the burnishing by the co-operation of two members and urged toward the burnishing member by the action of one or both of said advancing members. Herein is disclosed a work- 20 supporting member which exerts this lateral force by transverse ribs upon its work-engaging periphery, and a pressure member which acts by movement against the work in an inclined direction. Heat is preferably applied to the 25 burnishing member by an electrical device presenting an extended heating surface along which said member moves. Adjustments are furnished for the burnishing member, the pressure member and the heating member, whereby their relation 30 may be varied as the work in hand requires.

In the accompanying drawings of a particular embodiment of my invention,

35 Fig. 1 shows my improved machine in side elevation, parts being broken away;

Fig. 2 is an irregular section taken just above the heating unit and pressure-roll;

Fig. 3, a similar view taken above the slide 40 through which the burnishing tool is actuated; and

Fig. 4, an enlarged detail in elevation of portions of the work-supporting and pressure-rolls and the burnishing tool.

45 As appears in Fig. 1, a machine-frame 10 arranged for mounting upon a bench is provided with a lower horizontal arm 12 and an overhanging arm 14 divided at its outer extremity into lower and upper portions 16 and 18, respectively. Secured in a horizontal position upon the arm 12 is a table 20 having a slot through which projects the periphery of a work-supporting roll 22. The work-engaging surface of this roll has transverse ribs 24, which are preferably inclined 50 inwardly and rearwardly, as viewed in Fig. 1.

The purpose of this ribbed formation will later be developed. The roll 22 is fast upon a horizontal shaft 26 journaled in the frame and joined by gearing 28, 28 and a vertical shaft 30 to a driving shaft 32 rotatable in the upper portion of the frame. Power may be applied to the shaft 32 through a belt 34. By this means the roll 22 is turned in an anti-clockwise direction as seen from the left in Fig. 1. The action of the roll is, therefore, to advance work, supported upon the table and indicated at W, from the operator's position at the front of the machine. A plate 35, secured to the table-top adjacent to the inner side of the roll 22 and covering a portion of the slot, supports the work beside said roll.

To hold the work against the roll 22 for its advance during the burnishing operation, there is secured in the frame-arms 16 and 18 a vertical spindle 36 to which is attached, by set-screws 38, extensions 40, 40 from a carrier-arm 42. The outer portion of the arm is divided at 44, 44, and in these divisions a spindle 46 is longitudinally movable in an inclined direction inwardly and downwardly. In a slot in the lower extremity of the spindle 46, a short bar 48 is clamped, and extending inwardly from this bar is a stub-shaft 50. Rotatable about this shaft is a pressure-roll 52, the periphery of which is frusto-conical, the angle being such that opposite the work-supporting roll 22 it will present a work-engaging surface transversely parallel thereto. The roll 52 is urged against the work, lying upon the table 20 and over the roll 22, by a spring 54 surrounding the spindle 46 between the upper arm-division 44 and a collar 56 secured to the spindle by a set-screw 58. By altering the position of the collar along the spindle, the force exerted by the spring may be increased or decreased. Projections 57 from the collar 56 at opposite sides of the carrier-arm 42 may prevent the rotation of the spindle 46. By clamping the collar at different angles about the spindle, the angle of the roll 52 about the axis of said spindle may be correspondingly changed. The extent of downward movement of the roll 52 may be variably determined by a collar 60, fixed to the spindle 46 by a set-screw 62 and engaging the lower arm-division 44. The vertical relation of the pressure-roll 52 and its angular relation about a vertical axis may be changed by shifting the carrier-arm 42 upon the spindle 36. To elevate the spindle 46 with the roll 52 for the introduction or removal of work, a lever 64 is shown as fulcrumed upon the frame-arm 14, it extending at one end beneath the collar 56. The lever 55

is normally held by a spring 66 against a stop 68 upon the frame, it then being clear of the collar. When the lever is rocked clockwise (Fig. 1) by a treadle-connection 70, it engages the 5 collar to raise the roll.

Oscillating close to the inner side of the bite of the rolls 22 and 52 is a burnishing tool 72. The operating portion of this tool lies in a substantially horizontal direction in the plane of the 10 work and has a concave face 74 for contact with the edge of said work. The shank 76 of the tool extends vertically and is attached by a slot-and-screw connection 78 to the depending arm 80 of an operating lever 82. A horizontal portion of 15 the lever is fulcrumed at 84 to a plate 86 which has opposite vertical flanges 88, 88 attached to the frame-arm-division 16. The plate is spaced sufficiently from the under side of the arm to receive the lever and a portion of its actuating 20 elements. In the lever, as appears in Fig. 3, is a slot 90 in which may move a slide 92. The slide is provided with a vertical opening to receive a projection 94, eccentrically formed upon the lower extremity of a shaft 96 journaled vertically 25 in the frame-arm-divisions 16 and 18. The shaft 96 is rotated by belt-gearing 98 from the shaft 32, to oscillate the lever 82 and thus move the tool 72 rapidly back and forth along the edge of the work. Said work is conveniently located to receive this 30 action by an edge-gage 100 adjustable toward and from the path of the work by a slot-and-screw connection 102. An adjustable abutment member 104 may be used to more securely retain the gage against displacement. The work-contacting end of the gage is shown as concaved at 35 106 to better guide the work.

To give the proper burnishing effect, the tool 72 is heated. For this purpose I prefer to use an electric unit 108 to which current is delivered 40 through conductors 109, 109. The unit is of such a character that it presents a heated surface 110 extending for a considerable distance along the path through which the tool oscillates. The unit may have grooved edges which receive op- 45 posite angular projections 112, 112 from the sides of a holder 114. This holder is shown as carried by the lower extremity of a supporting rod 116 which passes through a vertical opening in a bracket 120 and is secured therein by a set-screw 50 118. The bracket 120 is fixed by a slot-and-screw connection 122 to the arm-division 16. The mounting of the unit allows it to be adjusted both toward and from the burnishing tool and in a direction parallel to its shank, so the degree of 55 heat desired may readily be obtained. By mounting the unit in a fixed position independently of the movable tool, yet exerting a constant heating effect upon it, the supply of current and the organization generally may be much simplified.

60 In using the apparatus, a margin of a work-piece W is laid upon the table with the edge to be burnished positioned by the gage 100. To the edge, wax or other dressing may have been applied. To permit the introduction of the work, 65 the pressure-roll 52 will have been elevated by the treadle-connection 70, and when said work is in place, the treadle is freed to allow the spring 54 to force the pressure-roll against the work and the work against the supporting roll 22. The 70 amount of pressure is determined by the adjustment of the collar 56 upon the spindle 46. The driving shaft 32 being in rotation, the upper work-engaging surface of the supporting roll 22 is rotated away from the observer in Fig. 1. As 75 the ribs 24 engage the under surface of the work,

their inclination will cause them to tend to move it in two directions; that is, there will be a component of the force exerted circumferentially of the roll and a second component acting at right angles thereto. The first feeds the work forward, while the second urges it toward the gage 5 100 and against the burnishing surface 74 of the tool. At the same time, since the pressure of the roll 52, as a result of its inclined movement, is not only directed downwardly but also inwardly, 10 its engagement with the upper side of the work will force said work toward the tool and gage. The operator is thus largely relieved of the necessity of guiding the work and a firm contact of the burnishing surface with the work-edge is insured. 15 By combined use of the adjustments at 38, 62 and 78, the relation of the roll 52 to the margin of the work, both vertically and horizontally, and of the tool-surface 74 to the edge of said work, may accurately be attained. Current will be flowing 20 through the electric unit 108, and the tool 72 will be in oscillation and heated by the proximity of the surface 110. By the adjustments at 118 and 122, the amount of heat received by the tool is made sufficient to produce the proper burnishing effect. The desired extent of the edge of the work-piece having been subjected to the action of the tool, the machine is ready for the succeeding operation. It will be seen that the manner of presenting the work to the tool is most convenient 25 for the operator and that the mechanism by which said tool is actuated is simple and compact.

Having described my invention, what I claim as new and desire to secure by Letters Patent of 30 the United States is:

1. In an edge-burnishing machine, means for advancing work in a substantially horizontal plane, an actuating lever having a depending portion extending toward the work and with burnishing means extending from said depending portion in the plane of the work, and means for oscillating the lever.

2. In an edge-burnishing machine, means for advancing work in a substantially horizontal plane, a tool-actuating lever having a portion 45 extending vertically toward the work, means for oscillating the lever, and a burnishing tool provided with a shank secured to the lever and with a work-edge-engaging portion extending at an angle to the shank in the plane of the work.

3. In an edge-burnishing machine, a work-supporting table, work-advancing means co-operating with the table, a lever fulcrumed above the table and having a portion extending downwardly toward the advancing means, and a burnishing tool secured to the lever and provided with a portion extending substantially parallel to the table and having a concave end for engagement with the work-edge.

4. In an edge-burnishing machine, means for advancing the work in a substantially horizontal plane, a tool-operating lever having a depending portion extending toward the work, means for oscillating the lever, a burnishing tool provided with a shank secured to the lever and with a work-edge-engaging portion extending at an angle to the shank in the plane of the work, and means arranged to secure the tool in different positions upon the lever.

5. In an edge-burnishing machine, the combination with an overhanging frame, of means for feeding the work carrier thereby, a plate supported on and in parallel spaced relation to the under side of said frame, a slotted lever fulcrumed 70 75

- in the space between the frame and the plate and having a burnishing portion, an apertured slide in the slot of said lever and held therein by said plate, and a shaft rotatable in the frame about 5 the lever and provided with an eccentric portion journaled in the apertured slide in said space.
6. In an edge-burnishing machine, the combination with a frame having an overhanging arm, of work-supporting means carried by the frame 10 beneath the arm, a lever fulcrumed horizontally upon the arm and provided with a depending portion upon which is a burnishing surface, and means for oscillating the lever.
7. In an edge-burnishing machine, the combination with a frame having an overhanging arm, a plate secured to the arm and spaced from a surface thereof, a lever fulcrumed in the space and having burnishing means, means for oscillating the lever, and means for presenting work to the 15 burnishing means.
8. In an edge-burnishing machine, a movable burnishing tool, and feeding members engaging the work-margins at opposite sides of the edge to be burnished, both of said members exerting a 20 lateral force upon the work to urge its edge against the burnishing tool.
9. In an edge-burnishing machine, a movable burnishing tool, a work-feeding roll rotatable in engagement with the work, means for rotating 25 the roll, and a pressure member movable in engagement with the work at the opposite side from the feeding roll and in a direction inclined inwardly toward the tool to force the work both against the roll and against the burnishing surface of the tool.
10. In an edge-burnishing machine, a movable burnishing tool, a work-feeding roll rotatable in engagement with the work, the work-engaging surface having ribs extending transversely there- 30 of and being inclined with respect to the axis of the roll, means for rotating the roll to simultaneously advance the work and force it against the burnishing surface of the tool, a pressure-roll movable against the work at the opposite side 35 from the feeding roll, and a yieldable mounting for the pressure-roll movable in an inclined relation both toward the feeding roll and toward the burnishing tool.
11. In an edge-burnishing machine, a movable burnishing tool, a rotatable work-supporting roll situated at one side of the tool, a rotatable pressure-roll engaging the work at the side opposite 40 the supporting roll, a spindle upon which the pressure-roll rotates, a mounting through which 45 the spindle moves in a direction inclined inwardly toward the burnishing tool, and a spring forcing the spindle through the mounting toward the work and tool.
12. In an edge-burnishing machine, a movable 50 burnishing tool, a rotatable work-supporting roll situated at one side of the tool, a rotatable pressure-roll engaging the work at the side opposite 55 the supporting roll, a spindle upon which the pressure-roll rotates, a mounting through which the spindle moves in a direction inclined inwardly toward the burnishing tool, and a spring forcing the spindle through the mounting toward the work and tool.
- the supporting roll, a spindle upon which the pressure-roll rotates, a mounting through which the spindle moves in a direction inclined inwardly toward the burnishing tool, two collars secured to the spindle for adjustment longitudinally thereof, and a spring interposed between the mounting and one of the collars and acting to urge the pressure member toward the work and the other collar toward the mounting.
13. In an edge-burnishing machine, a frame, 10 a burnishing tool movable upon the frame in contact with the work, a work-supporting roll rotatable upon the frame in co-operation with the tool, a mounting movable upon the frame toward and from the work, means arranged to fix the mounting in different positions upon the frame, a pressure-roll movable upon the mounting in a direction inclined with respect to the direction of movement of the mounting, and a spring urging the pressure-roll toward the work.
14. In an edge-burnishing machine, a frame, 15 a burnishing tool movable upon the frame in contact with the work, a work-supporting roll rotatable upon the frame in co-operation with the tool, a spindle secured in the frame, an arm carried 20 by the spindle, means arranged to fix the arm in different positions upon the spindle, and a pressure member movable upon the arm.
15. In an edge-burnishing machine, a frame, 25 a burnishing tool movable upon the frame in contact with the work, a work-supporting roll rotatable upon the frame in co-operation with the tool, a substantially vertical spindle secured in the frame, an arm carried by the spindle, a spindle movable upon the arm in a direction inclined 30 downwardly and inwardly toward the work-supporting roll, a pressure-roll rotatable upon the spindle for contact with the work, and a spring urging the pressure-roll toward the work-supporting roll.
16. In an edge-burnishing machine, means for advancing the work, a burnishing tool, means for oscillating the tool along the path of the work, a holder variable in position with respect to the tool, and an electrical heating device mounted 35 upon the holder for heating the tool.
17. In an edge-burnishing machine, means for advancing the work, a burnishing tool, means for oscillating the tool along the path of the work, a holder variable in position in a plurality of directions at different angles to one another, and an electrical heating device mounted upon the holder for heating the tool.
18. In an edge-burnishing machine, a frame, 40 means movable thereon for advancing the work, a burnishing tool movable in the frame, a bracket variable in position upon the frame, a holder variable in position upon the bracket, and an electrical heating device mounted upon the holder.

GEORGE BOULTON.
